DISPLAY STAND

John G. Fettinger, Utica, N. Y., assignor to Robert Gair Company, Inc., New York, N. Y., a corporation of Delaware

Application April 30, 1947, Serial No. 744,890

5 Claims. (Cl. 206—45.11)

1

This invention relates to a display stand, and more particularly to a combination shipping carton and display stand.

Most shipping cartons or containers that have been designed to be used also as display cartons require more or less intricate remaking or adjustment, or both, in order to be converted into a display carton or stand. Also, most of such containers are designed so that they can be used only in one position as a display, and while this may be satisfactory in small cartons to be placed on top of a show case or the like, it is not always satisfactory with larger displays of the type adapted to stand on the floor.

One object of this invention is to provide a combination shipping container and display stand composed of separate box sections joined together so that they may be folded together for shipment and opened up to serve as a satisfactory display stand either along a flat wall or in a corner.

A further object of the invention is to provide such a display stand which is fashioned economically from a pair of substantially rectangular blanks properly scored, cut and folded.

A further object of the invention is to provide such a device which can be assembled and shipped flat to a manufacturer who can then easily and quickly adjust the device to receive his goods for shipment.

Other objects and advantages of the invention will be explained or will be apparent from the following description of a preferred embodiment of my invention illustrated in the drawings, in which

Figure 1 is a front elevational view of my combination shipping container and display stand showing the device arranged for use as a corner display stand.

Figure 2 is a top plan view of the device in the same position shown in Figure 1.

Figure 3 is a front elevational view of the device showing the box sections folded together in position for use as a shipping container.

Figure 4 is a plan view of the blank used to form the back and adjacent side walls of the box sections of the device.

Figure 5 is a plan view of another blank used to form the front and remote side walls of the box sections of the device.

Referring to the drawings, and particularly to Figures 1, 2 and 3, the device is composed of a pair of separate box sections 10 and 11 made of any suitable material such as cardboard, paperboard, corrugated cardboard or the like. Each box section has relatively tall, plain back walls 12, 12 and forward or front walls 13, 13 of reduced height. The box sections are also provided with side walls 14, 15 located adjacent each other and shorter side walls 16, 17 located at the sides of the box sections remote from each other. The box sections are hinged together by a joint 18 formed along the forward edges of the adjacent side walls 14 and 15.

Since the side walls 14, 15 are integral with each

2

other and the forward walls 13, 13 are integral with each other as will be explained hereinafter, the hinged joint may be formed by cutting the tabs 19a and 19b out of the side walls 14 and 15, folding these tabs against the inner surfaces of the forward walls 13, 13 and securing the tabs in place by suitable means such as the staples 19. Other methods of forming this hinge joint may, of course, be employed. In fact for some purposes, it may be sufficient to secure the side walls 14, 15 to the forward walls 13, 13 simply by a series of staples applied in a vertical line where these four walls come together.

15 The remote side walls 16, 17 may be provided with tabs 20, 21 at their upper ends, which can be raised to a vertical position, but which are preferably folded down inside their respective box sections when the carton is used as a shipping container or as a display stand. Likewise, the upper portions of the forward or front walls 13, 13 may be scored along the diagonal lines 22, 23 to provide tabs 24, 25 which can be raised to an up-standing position, but which are preferably folded down inside their respective box sections when the carton is used as a shipping container or as a display stand. These tabs 20, 21 and 24, 25 thus provide smooth upper edges for the front walls 13, 13 and the side walls 16, 17.

30 The upper portions of the adjacent side walls 14, 15 may be cut along the zigzag offset line 26 and scored diagonally downward along the lines 27, 28 to provide the tabs 29, 30. Thus, when the device is used as a shipping container in the form shown in Figure 3, these tabs 29 and 30 become extensions completing the end walls 14, 15. When the device is used as a corner display stand, however, the tabs 29, 30 are folded back and interlocked together as indicated in Figure 2 to provide 40 a bi-planar inclined surface fitting into a corner in which the display stand may be arranged. If desired, the zigzag cut line may be replaced by a single straight score line to obtain the same appearance without the interlocking feature.

45 The box sections may be provided also with bottom walls 31, 32 having extensions or tabs 33, 34 which in assembled position lie inside and along the back walls 12, 12, and may be secured in place in any desirable manner.

50 Referring now more particularly to Figures 4 and 5, it will be apparent that the blank shown in Figure 4 can be readily formed from a rectangular piece of suitable material by simply scoring it along the lines 35, 36 and 37 to provide the back walls 12 and the side walls 14, 15. Along the center of the blank at the top, the zigzag line 26 may be cut and the score lines 27, 28 formed to provide the tabs 29, 30. Tabs 19a and 19b may be cut out to fold about the score line 36 as previously described.

The remainder of the box can be formed from a second blank shown in Figure 5, which again

is generally of simple rectangular shape and scored centrally along the line 38 to form the forward walls 13, 13. The remote side walls 16, 17 may be formed by similar score lines 39, 40, the extensions of these score lines being cut at 41, 42, 43 and 44. Thus, the additional score lines 45, 22, 23 and 48 provide for the tabs 20, 21 and the tabs 24, 25 in the upper portions of the front and side walls. At the bottom the blank may be scored along the line 49 to provide the bottom walls 31, 32 and also scored along the lines 50, 51 to provide the tabs 33, 34. Tabs 52, 53 may be provided at the bottom of the side walls 16, 17 and the small tabs 54, 55 may be provided at the sides of these side walls 16, 17.

Thus, in assembling the device, the blanks are folded along the lines as indicated and the two blanks are brought together so that the score line 38 is superimposed on the score line 36, with the tabs 19a and 19b against the back of walls 13, 13. These walls 13, 13 may then be secured to the tabs 19a and 19b by staples or other suitable means to provide the hinge joint 18 (Fig. 1). The tabs 54, 55 are then folded around the back walls 12, 12 and secured in place by means of adhesive, or staples 56 (Figure 3) or the like. In this form the two blanks are roughly assembled and may be shipped flat to the manufacturer.

The assembly of the box sections is then easily completed by opening the sections to form separate boxes, folding in the tabs 52, 53 tucking in and securing the tabs 33, 34 to complete the bottom walls. The two box sections are then ready to be loaded with goods for shipment and folded together as shown in Figure 3 with the two back full size walls 12, 12 on the outside. The shipping carton may readily be completed by sliding an open end box unit over its top, or by any other suitable outer wrapping or covering.

In order to use the device as a corner display, it is simply necessary to remove the outer wrapping and open the box sections to a position approximately at right angles to each other with the tabs 29 and 30 bent backward as shown in Figures 1 and 2.

The device may also be used as a display stand along a completely flat wall, and for this purpose the tabs 29, 30 may be disengaged and moved up to a position in the same plane with the walls 14 and 15, or they may be folded back to lie against the inside portions of the walls 14, 15. In either case, the box sections may then be opened out so that they lie parallel and side by side, or they may be opened out to any desired angle less than 180°.

It will be apparent that by using two separate blanks, the device of my invention may be readily fashioned with much less waste or loss of material than by trying to make it from a single blank. In any event, however, the device provides a convenient practical shipping container which can be adapted very easily by a retailer to the type of display stand best suited for any available location in his store.

A particular advantage of my new carton is the ease with which the retailer may convert it from a shipping container to a display carton by merely removing the outer wrapping and opening the box sections to the desired position. A carton of this type is also eminently suited for the display of long thin objects which otherwise would tip over.

The terms and expressions which I have employed are used as terms of description and not

of limitation, and I have no intention, in the use of such terms and expressions, of excluding any equivalents of the features shown and described or portions thereof, but recognize that various modifications are possible within the scope of the invention claimed.

I claim:

1. A display carton comprising separate box members arranged side by side and connected together by a hinge joint along adjoining forward side edges so that said box members can be set up in a corner or along a flat wall, the forward walls of said members extending only part way to the top thereof, and upper portions of adjacent side walls of said members being scored and folded to form an inclined surface when the carton is set up in a corner.

2. A combination shipping and display carton which comprises a pair of box sections arranged side by side, the forward walls and remote side walls of said sections being shorter than the other walls and formed from a single blank, the back and adjacent side walls of said sections being formed from a single blank, and said sections being hinged together along the junction of the forward edges of said adjacent side walls.

3. A combination shipping and display carton which comprises a pair of box sections arranged side by side, the forward walls and remote side walls of said sections being shorter than the other walls and formed from a single blank, the back and adjacent side walls of said sections being formed from a single blank, said sections being hinged together along the junction of the forward edges of said adjacent side walls, and upper portions of said adjacent side walls being scored diagonally and folded to form an inclined surface when said sections are turned at right angles to each other.

4. A combination shipping and display carton comprising a pair of box sections hinged together so that said sections can be folded together or extended in side by side relation, the adjacent walls of said sections when folded together being shorter than their opposite walls, and adjacent side walls of said sections having upper portions that can be folded and interlocked with each other to provide inclined surfaces when said sections are turned at right angles to each other.

5. A combination shipping and display carton which comprises rear walls and adjacent side walls of two box sections formed from a single sheet of material, and front, bottom and remote side walls of said sections formed from a separate single sheet of material, the edges of said front and adjacent side walls of said sections meeting and being joined along a single line to form a hinge joint for said sections.
